UNITED STATES PATENT OFFICE.

FRANK J. SCHALOW, OF EAST NEW YORK, N. Y.

DESIGN FOR A CREASE-RETAINING DEVICE FOR HATS.

57,996.

Specification for Design.

Patented May 24, 1921.

Application filed February 24, 1920. Serial No. 360,999. Term of patent 14 years.

To all whom it may concern:

Be it known that I, FRANK J. SCHALOW, a citizen of the United States, and residing in East New York, in the county of Kings and State of New York, have invented a new, original, and ornamental Design for a Crease-Retaining Device for Hats, of which the following is a specification, reference being had to the accompanying drawing, forming part thereof.

Figure 1 is a plan view of a crease re-

taining device for hats, showing my new design.

Fig. 2 a side view thereof; and,
Fig. 3 an end view thereof.

I claim:—

The ornamental design for a crease retaining device for hats, as shown.

FRANK J. SCHALOW.
